UNITED STATES PATENT OFFICE.

ALEXANDER HARPER AND STEWART ALEXANDER HARPER, OF DUNEDIN, OTAGO,
NEW ZEALAND.

PROPELLER.

Application filed July 18, 1925. Serial No. 44,533.

This invention relates to apparatus used for propelling vessels, and in particular to the propulsion of sea-going vessels.

The action of the marine propeller should force the water straight astern, and not throw it off the ends of the blades laterally, as occurs to a great extent with ordinary screw propellers. When a propeller of too great a pitch is used, or in the case of a three blade propeller of small diameter turning at high speed, churning is the result, and it is an established fact that a two-blade propeller will procure a larger volume of solid water when run at high speed than a three-blade propeller, which is apt to churn, as there is less chance of the water passing through the blades freely. As a propeller working in water performs exactly as it does in the air, the only difference being that in each case the propeller is used in conjunction with a different element, there is no reason why it should not be used with equal merit on air vehicles.

The object of the invention is to provide an improved propeller of the type herein described and illustrated in the accompanying drawings, having two or more blades, according to the size and purpose for which it is to be used for the more efficient propulsion of vessels than hitherto attained with the ordinary propeller, this being accomplished by using a propeller fashioned as illustrated, the revolutions of the said propeller being increased or/and reduced in velocity in relation to the speed of the vessel without undue loss of efficiency, this being due principally to churning and slip experienced with the ordinary propeller.

Referring to the drawings accompanying this specification,

Figure 1 is a view of a propeller fashioned in accordance with my invention, the illustration showing the said propeller in a vertical position with its boss uppermost.

Figure 2 is an elevation of Figure 1.

There is a boss 1, similar to that used with an ordinary propeller, having a centrally disposed hole 2 of suitable diameter to fit a tail shaft or propeller shaft, the said

hole being preferably tapered from the end 50 face 3 of the boss to produce a larger orifice at the opposite end face 4 thereof; a keyway 5 to enable the boss 1 to be keyed to a suitable shaft is cut along the hole 2, parallel with the axis of the said hole 2.

There are preferably two blades 6, which are secured by the part 7 to the boss 1 by suitable means, or cast integral with it to extend away from the said boss 1 in a direction almost parallel with the axis of the 60 hole 2 therein. The profile of the said blade 6 is wavelike in form, the trough or concave portion 8 starting from the outside tip of each blade, and extending in towards the central revolving axis of the two blades 6, 65 and in doing so forming a swell or convex portion 10 throughout the entire length of each blade. The diameter from tip to tips 9 of each blade 6 may be referred to as the "major" diameter, and the over-all distance 70 from 11 to 12 at the smaller end as the "minor" diameter of the propeller, the said wavelike formation extending for the entire length of each blade, and diminishing 75 in wave-length towards the smaller end thereof.

A propeller fashioned in accordance with my invention from sheet metal would in its blank form be in the shape of a keystone, one end being much larger than the other, or would appear like the section of a truncated cone; the sheet of metal would be cut along the broken lines 13, the metal encompassed by the said broken lines 13 being discarded, the edges 14 and 15 being bent round 80 opposite to each other. The edges 16 and 17 are then bent round so as to be opposite each other, and yet opposite in direction to their innermost edges 14 and 15 respectively. The wave would then be formed in each 85 blade 6, the radius thereof reducing gradually from the major diameter to the minor diameter and the wave formation becoming less prominent.

What we claim as new and desire to secure 90 by Letters Patent is:—

A propeller of the character described, including a shaft engaging boss, blades ex-

tending radially in opposite directions from the boss and also extending rearwardly and arranged in substantial parallelism with the longitudinal axis of the boss, the profile of the blades being wave-like in form and the inner marginal edges of each of the blades being bent in a wave-like manner in a direc-

tion opposite the wave-like main portion of each blade, substantially as and for the purposes set forth.

In testimony whereof we have hereunto set our hands.

ALEXANDER HARPER.

STEWART ALEXANDER HARPER.
